UNITED STATES PATENT OFFICE

116,192

DESIGN FOR A CITRUS FRUIT PEELER

Paul J. Ouellette, Pasadena, Calif.

Application June 12, 1939, Serial No. 85,453

Term of patent 14 years

To all whom it may concern:

Be it known that I, Paul J. Ouellette, a citizen of the United States, residing at Pasadena, in the county of Los Angeles and State of California, have invented a new, original, and ornamental Design for Citrus Fruit Peeler, of which the following is a specification, reference being had to the accompanying drawing, forming a part thereof.

Fig. 1 is a side elevation of a citrus fruit peeler showing my new design, the essential features of which are illustrated in full lines.

I claim:

The ornamental design for a citrus fruit peeler, substantially as shown and described.

PAUL J. OUELLETTE.
